US0D1054348S

(12) **United States Design Patent** (10) Patent No.: **US D1,054,348 S**
(45) Date of Patent: ** Dec. 17, 2024

(54) **CALIPER FOR BRAKE DISC**

(71) Applicant: **Brembo S.p.A.**, Curno (IT)

(72) Inventors: **Mauro Mambretti**, Curno (IT);
Tommaso Moricci, Curno (IT); **Davide Boleso**, Curno (IT); **Zhen Chen**, Nanjing (CN); **Jim Zhang**, Nanjing (CN); **Shuming Wang**, Nanjing (CN); **Xian Yang**, Nanjing (CN); **Simone Masi**, Curno (IT); **Yuwei Zhong**, Nanjing (CN); **Lorenzo Nessi**, Curno (IT)

(73) Assignee: **Brembo S.p.A.**, Bergamo (IT)

(**) Term: **15 Years**

(21) Appl. No.: **35/515,752**

(22) Filed: **Nov. 22, 2022**

(80) **Hague Agreement Data**

Int. Filing Date: **Nov. 22, 2022**

Int. Reg. No.: **DM/225153**

Int. Reg. Date: **Nov. 22, 2022**

Int. Reg. Pub. Date: **Dec. 9, 2022**

(51) **LOC (14) Cl.** 12-16
